UNITED STATES PATENT OFFICE.

HENRY E. EBERHARDT AND FRED L. EBERHARDT, OF NEWARK, NEW JERSEY, ASSIGNORS TO GOULD & EBERHARDT, OF NEWARK, NEW JERSEY, A CORPORATION OF NEW JERSEY.

GEAR-CUTTING MACHINE.

SPECIFICATION forming part of Letters Patent No. 727,761, dated May 12, 1903.

Application filed February 27, 1902. Serial No. 95,936. (No model.)

To all whom it may concern:

Be it known that we, HENRY E. EBERHARDT, residing at 113 Orchard street, and FRED L. EBERHARDT, residing at 17 Hillside avenue, 5 Newark, Essex county, New Jersey, citizens of the United States, have invented certain new and useful Improvements in Gear-Cutting Engines, fully described and represented in the following specification and the accompanying drawings, forming a part of the same.

The present invention relates to that class of gear-cutting machines in which the cutter-carriage is reciprocated parallel with the spindle of the gear-blank, such spindle being adjustable to and from the cutter-head to support blanks of various sizes in the proper relation to the cutter. Such machines are commonly constructed with a horizontal bed having ways upon which the cutter-carriage is reciprocated horizontally and a vertical column at one end of the bed upon which a head is adjustable vertically to carry the blank-spindle. In such machines disk cutters have always heretofore been used, and with such construction only spur-gears can be cut, as the cutter is necessarily traversed parallel with the blank-spindle.

The principal object of this invention is to adapt such machines to cut spiral gears by placing a certain attachment upon the reciprocating carriage to support an end-milling cutter upon a vertical spindle. In machines of this class it is common to form the horizontal cutter-arbor with a socket into which the shank of the cutter-spindle can be fitted, and in the present invention the end-milling cutter is driven by gearing which is connected with a shank fitted to the socket in the cutter-arbor interchangeably with the cutter-spindle.

By the use of an end-milling cutter the traversing of the cutter parallel with the blank-spindle does not prevent the formation of spiral teeth, as the blank-spindle and the blank 45 may be rotated gradually during the cutting of the tooth and the tooth thus inclined spirally to the axis of the blank. The blank-spindle for supporting the gear-blank is usually fitted to a tapering socket in a rotatable 50 support or sleeve, to which the indexing-wheel

is attached, and the blank-spindle is commonly drawn into the tapering socket by a locking-screw with collar adjacent to the indexing-wheel. By fitting a cap around the outer end of the screw and attaching the same 55 to the blank support or sleeve the collar may be sustained when the locking-screw is reversed to push the blank-spindle from its socket.

We have found that a hand-wheel of very 60 moderate size suffices to turn the screw for locking the spindle in the socket, but that the same hand-wheel is often unable to force the spindle from the socket by reversing the locking-screw when the spindle becomes accidentally jammed in its socket. To quickly dislodge the spindle by means of such locking-screw, we provide two levers of materially different lengths upon the outer end of the locking-screw and use the shorter one for locking the spindle and the longer one for unlocking the same. To prevent the use of the longer lever for locking the spindle, we connect it detachably with the screw by a ratchet with sloping teeth which permits the longer lever 70 to turn the screw in one direction only—that required for expelling the blank-spindle.

Pans of various kinds have been placed around the bed of a gear-cutter to catch the oil which drips from projecting bearings, and 80 especially to receive the chips and oil discharged from the cutter when the latter is cutting metals which require lubrication, and a pump is often used to lift the oil continuously from the pan and throw it upon the cutter. The accumulation of oil in such pans is a great source of annoyance, as tools, nuts, and other objects are liable to fall into the oil, and thus become temporarily lost or soiled with the oil, and the projection of such pan 85 from the bottom of the bed upon the floor interferes very seriously with the close access of the operator to the machine. As the operator when setting a gear and cutter requires to inspect them very closely, the pan forms a 90 serious obstruction to the access of the operator and compels him to lean over in a very uncomfortable manner.

The present invention provides a floor-pan 95 in which the oil-trough is raised above the 100

level of the floor and overhung upon a base of sufficient size to adequately support the machine, but not interfere with the operator's standing as close to the bed as is necessary.

5 By thus raising the oil-trough opportunity is afforded in the pan below the bottom of the trough to form a tank to hold the stock of oil, and thus prevent its accumulating in the trough.

10 In practice it is preferred that the chips and oil discharged from the cutters should fall through an aperture in the bed, and in such case a platform is arranged above the level of the trough to facilitate the drainage of the 15 oil from the chips and the transmission of the oil to the tank comparatively free from sediment. The tank is formed with partitions projecting upwardly a suitable distance from the bottom, near the edges of the tank, to 20 skim the oil as it enters the tank, and thus arrest the sediment near its edges. In the space between such partitions the pipe of a suction-pump may draw the oil quite clean to feed it to the cutter. The gearing to reciprocate the carriage is commonly extended 25 from the front end of the gear-cutter bed, and the pan is correspondingly extended from the forward edge of the base to catch any oil that drips from such gearing.

30 At one side of the machine, where the operator stands, the trough is preferably formed as a narrow channel to catch any oil which runs down the edge of the machine, but not to obstruct the close access of the operator to 35 the machine. Upon the opposite side of the machine the tank may be conveniently located without interfering with the operator, and the trough may be extended around the rear end of the machine to catch any drip from 40 projecting parts and then connected with the rear end of the tank. All parts of the trough are formed with an inclination toward the tank, and to limit as much as possible the flow of oil toward the front of the machine, 45 where its appearance is most unsightly, the channel upon the operator's side of the machine is preferably inclined from the front of the bed to the rear end to discharge its oil into the rear end of the tank. The ends of 50 the tank-cover are raised a little above the bottom of the trough to permit the oil to enter without flowing upon the top of the cover, and the appearance of the whole arrangement is thus rendered more neat and cleanly.

55 The invention will be understood by reference to the annexed drawings, in which—

Figure 1 is a side elevation of a gear-cutter having horizontal bed and vertical column to sustain the gear-blank adjustably, 60 the floor-pan being shown in section at the bottom of the machine. Fig. 1^a shows the worm-spindle, and Fig. 1^b the floor-pan cover. Fig. 2 is a plan of the floor-pan, and Fig. 3 a cross-section at the front end of the tank. 65 Fig. 4 is an elevation of the gear-cutter with the base and the cutter-carriage and adjacent parts in transverse section at the center line

of the cutter-driving arbor. Fig. 5 is a plan of the cutter-carriage with the end-milling cutter mounted thereon as in Fig. 4. Fig. 6 is an end elevation of the cutter-carriage with a part of the bed in section where hatched and the cutter-arbor provided with a disk cutter. Fig. 7 is a detail of the gear-spindle for the end-milling cutter. Fig. 8 is 75 a sectional plan of the blank-spindle support and its attachments at the center of the spindle, only the parts being shown in section where they are hatched. Fig. 9 is a section of a part of the attachments at the rear end of 80 the locking-screw. Fig. 10 is a cross-section of the same on line 10 10 in Fig. 9; and Fig. 11 is a section of the gear-blank support, showing a modification of the locking-screw.

The machine illustrated is of the type shown 85 in Eberhardt's Patent, No. 575,393, issued January 19, 1897.

The horizontal bed *a* of the machine is shown with vertical column *b* at one end, carrying a head *c*, in which the rotary spindle-support *d* is fitted to carry a horizontal blank-spindle and provided with indexing-wheel *e*, with worm *f* to turn the same. A carriage *g* is shown fitted to reciprocate horizontally upon the bed to and from the column and is 95 provided with the usual feed-screw *g'* and with a horizontal cutter-driving arbor *h*, arranged transverse to the movement of the carriage.

A driving-shaft *c'*, which would be provided with a pulley for driving the same, is connected by gearing with a side shaft *k*, extended through bearings *k'* upon the cutter-carriage to a casing *l* upon the front end of the bed, in which the usual gearing is commonly 105 arranged to transmit the power of the driving-shaft to the feed-screw *g'*, if it is desired to reciprocate the carriage automatically. A shaft *K* is shown connected by change-wheels *m* and graduated wheel *m'* to the indexing 110 worm-shaft *f'*. The wheel *m'* turns loosely upon the shaft between its bearing and a crank *n*, which is furnished with a pointer or pin *n'* to set to the graduations upon the graduated wheel. The crank is attached to 115 the worm-shaft, and when the pin *n'* is engaged with holes *o* in the graduated wheel the rotations of the change-wheels turn the worm *f* and rotate the index-wheel. Such action is desired in cutting worm or spiral teeth upon 120 the gear-blank, the crank and graduations being used to turn the worm within the graduated wheel after cutting each spiral tooth for spacing the several teeth at the required distance. The devices for conveying 125 a variable motion from the driving-shaft to the worm-shaft and for spacing the teeth are wholly immaterial, as their nature is already well known and may be varied in any desired manner without affecting this invention.

The cutter-arbor *h* is shown in Fig. 6 mounted in a horizontal bearing *H'* at right angles to the movement of the cutter-carriage and provided with a socket to which the shank of

the cutter-spindle h^2 is fitted removably. A disk cutter is shown secured between sleeves h^4 upon the spindle h^2 by nut h^5 , and an out-board-bearing h^6 is shown fitted to the outer 5 end of the cutter-spindle to steady the same, being secured detachably upon a seat h^7 on the carriage. With such a construction the end-milling cutter can be readily applied to the carriage, as shown in Figs. 4 and 5, by 10 removing the cutter-spindle h^2 from the cutter-driving arbor h and removing the out-board-bearing h^6 and substituting a vertical bearing H , having a vertical cutter-shaft I therein, with socket for the shank J of the 15 end-milling cutter H' . The shaft I is shown formed with a bevel-gear I' upon the top, and a gear-spindle J' is shown fitted to the socket in the cutter-driving arbor interchangeably with the shank of the cutter-spindle h^2 and 20 provided with gear I^2 , adapted to drive the gear I' . The bearing H is shown with a foot H^6 , adapted to fit upon the seat of the out-board-bearing h^6 , and with feet H^8 , adapted to straddle the bearing H^5 of the cutter-driving 25 arbor.

The fastenings which secure the feet of the bearing to the carriage are constructed to always hold the bearing in the same position, with the axis of the end-milling cutter H' directed toward the blank-spindle at right angles thereto, and the bearing, with its spindle and gearing, thus constitutes an attachment which may be applied with perfect accuracy to the cutter-carriage in the position required 35 to support the end-milling cutter. The gear-spindle J' being fitted to the socket in the cutter-driving arbor interchangeably with the shank of the cutter-spindle h^2 , the attachment can be applied without any particular 40 skill and requires no adjustment to place the end-milling cutter in operation. The bearing H is preferably provided with a housing or guard to prevent chips produced by the milling-cutter from falling into the gearing 45 which drives the same, and as such guard covers the gearing the gearing is necessarily separable to permit the bearing H to be removed from the carriage before removing the cutter-gear I' from the spindle-gear I^2 . Such 50 detachability is effected by the use of the bevel-gears thereon, and the chips are excluded from the same by extending a housing G from the top of the spindle-bearing H over the gear I^2 and applying a guard i closely 55 to the top of such housing and to the gear I' at the base of the milling-cutter.

The guard i is shown in Fig. 4, but omitted from Fig. 5. It is preferably attached to the housing by screws, as indicated by the 60 holes i^5 in Fig. 5, and the gear I' revolves in close contact with it.

The housing is extended over the top of the gear I^2 , and at all other points around the bearing H it is extended outwardly and provided with a marginal flange to form a trough G' , in which the oil and chips fall from the cutter and from which the oil flows by a spout

G^2 at the rear side. The oil thus falls at the rear end of the carriage and escapes through the bed to the platform A , where its sediment 70 is settled before it runs to the tank. The bearing H with its feet and oil-trough and the shank carrying the bevel-gear I' form a very compact attachment, which may be connected in a few minutes with the driving-arbor by removing the cutter-spindle and substituting the gear I^2 with its shank J' . The 75 spindle J is set vertically underneath the blank-spindle and is thus adapted to sustain an end-milling cutter in the right relation to the gear-blank whatever the pitch of the teeth or the size of the end-milling cutter. This is not the case with any machine employing disk cutters, as the cutters of different pitches are made of various thicknesses and pressed against a collar or shoulder upon a cutting arbor or spindle by a clamping-nut or its equivalent. The adjustment of such varying cutters against the same shoulder would throw the center of the different cutters into different positions, and it is therefore common in applying different-sized cutters to the cutter-spindle of a gear-cutting machine to use bushings and sleeves of various kinds to center the cutter or to 80 make the entire cutter-arbor adjustable longitudinally. In either case it is necessary to use a plumb-line or suitable gage to set the cutter centrally, and any error or negligence in this respect produces defective teeth in the 85 gear-blank.

The necessity of setting each cutter centrally and the possibility of error or negligence of setting it accurately are not encountered in the use of end-milling cutters, as the 90 location of the cutter-spindle is unvarying in its relation to the blank-spindle whatever sized end-milling cutter may be employed. The feet of the vertical bearing H may thus be constructed to fit accurately in the required position upon the reciprocating carriage g and may always be secured thereon in the same position when applied for the purpose of cutting spiral gears.

The end-milling cutter may when desired 115 be used for roughing out or finishing the teeth of spur-gears, and a great increase in the capacity of a given gear-cutting machine is secured by using the end-milling cutter, either for cutting spur or bevel gears, by reason of 120 the diminished radius of the cutter-teeth upon an end-milling cutter as compared with the radius of a disk cutter to make teeth of a given size.

The disparity in the capacity of an end-milling-cutter, as compared with a disk cutter can be observed by comparing the cutters and the blanks shown in Figs. 4 and 6, respectively. In Fig. 4 the blank-spindle D is shown with gear-blank E having space E' cut 130 in the blank at one side of a tooth E^2 , while in Fig. 6 a blank is shown with similar spaces cut by a disk cutter. The two figures are drawn upon the same scale, and the teeth and the

spaces formed by the end-milling cutter shown in Fig. 4 being three times the size or pitch of the teeth and spaces formed by the cutter shown in Fig. 6. Notwithstanding such increased pitch the diameter of the end-milling cutter at the widest portion of the space between the teeth in Fig. 4 is only half as great as the diameter of the cutter shown in Fig. 6, while the point of the end-milling cutter has a cutting radius of only one-quarter the diameter of the disk cutter. The power required to drive such end-milling cutter is thus utilized to form teeth very much greater than any teeth which can be formed with a disk cutter with the same power, and the provision of such an attachment as we have claimed herein enables an end-milling cutter to be frequently used with advantage in machines having the carriage fitted to rigid ways upon the bed of the gear-cutter, so as to travel always parallel with the blank-spindle.

The use of a milling-cutter also saves a great deal of expense in the cutters themselves, as a milling-cutter is only about one-third as costly as a disk cutter to cut teeth of the same pitch. It will readily be seen by inspection of Fig. 6 how greatly the disk cutter would have to be enlarged in diameter and thickness to cut the teeth shown in Fig. 4. The end-milling cutter thus costs less and consumes less power to operate. The use of our attachment permits the formation of spiral teeth upon a blank in machines having no turn-table to set the cutter-arbor at any other than a right angle to the blank-spindle, as an end-milling cutter can move through a spiral tooth-space while propelled parallel with the gear-spindle and does not require to be inclined to the same angle as the space like a disk cutter.

The carriage shown in the drawings is fitted to ways g^2 in the top of the bed a , so as to travel always parallel with the blank-spindle D , and the bearing H^b of the cutter-driving arbor h is shown fixed permanently at right angles to the ways, as is common in machines designed exclusively for cutting spur-teeth. Many of such machines are now in use which can be utilized to cut gears with spirally-inclined teeth by the use of our attachment having an end-milling cutter with its axis directed toward the blank-spindle and a connection of the carriage-feed shaft with the worm of the indexing-wheel to turn the gear-blank through the desired arc as the cutter progresses across its periphery. In the example shown in the drawings the shaft k , which would be connected with the feed-gearing, and the change-wheels m , driven by such shaft, represent the means for rotating the indexing-wheel e to turn the blank gradually during the cutting of a spiral tooth, while the crank n and graduated wheel m' represent the means for spacing the teeth, and in machines of the class shown in the aforesaid patent, No. 575,393, a frictionally-driven change-wheel shaft is used, with a connection

to the cutter-carriage to release the change-wheels intermittently, so that the indexing-wheel may be turned to space the blank when the feed-carriage is retracted and the cutter withdrawn from the blank. Such machines require no change when an end-milling cutter is provided to cut spiral teeth except a connection between the feed-gearing and the indexing worm-spindle to turn the blank continuously during the cutting of the teeth and to reverse the motion of the indexing-wheel when the cutter-carriage is retracted. The particular means for effecting these objects or for spacing the teeth upon the blank forms no part of the present invention, and it is immaterial how they are constructed and whether or not they operate automatically.

The blank in cutting spiral teeth is commonly turned backward after the cutting of each tooth to restore it to its initial position, the indexing-wheel being turned in addition sufficiently to space the blank for cutting a succeeding tooth. Such movements of the blank are necessarily effected when the cutter is withdrawn from the blank. This invention permits the cutting of spiral teeth in gear-cutters having the cutter-arbor fixed at right angles to the blank-spindle and incapable of adjustment at any other angle which would be required to turn the disk cutter at an inclination to the path of the carriage, and the means for turning and indexing the blank are therefore immaterial.

The means for releasing the blank-spindle by reversing its locking-screw are shown in Figs. 8 to 11, inclusive, the head c being shown in Fig. 8 with the rotary blank-support d provided with the blank-spindle D , in the rear end of which a threaded socket is shown to admit the locking-screw p . The locking-screw is extended outwardly through the rear end of the spindle-support d to receive the operating-levers and is provided with a collar p' , (shown in Fig. 8,) fitted against the rear end of the support d , and in Fig. 11 with a collar p^2 at the bottom of the socket in which the blank-spindle D is fitted.

In Fig. 8 a hand-wheel P is shown attached to the shank of the locking-screw to turn the same when securing the spindle D in its socket, and an unlocking-lever Q of much greater radius than the hand-wheel is provided to unlock or discharge the blank-spindle. The collar p' (with the construction of Fig. 8) presses hard upon the rear end of the spindle-support d during the locking of the blank-spindle; but in reversing the motion of the locking-screw to force the spindle from the socket the collar p' is pressed outwardly and a cap P' is attached to the end of the spindle-support d to resist such outward thrust, and the unlocking-lever Q is shown fitted loosely to the shank of the screw p and provided with ratchet-teeth q to engage similar teeth attached to the locking-screw by the hub of the hand-wheel. A collar r is fixed upon the extreme end of the locking-screw

to hold the unlocking-lever when the teeth q clear those attached to the locking-screw.

When it is necessary to unlock the spindle D and force it from its socket, the teeth q engage with those upon the hand-wheel, and a greatly-increased leverage is afforded to the operator for turning the locking-screw backward. It is obvious that the hand-wheel affords the operator a leverage equal to its radius and is therefore equivalent to a star-wheel of the same diameter or to a single lever or arm of the same radius.

In Fig. 8 corresponding ratchet-teeth are formed upon the adjacent faces of the hub of the hand-wheel P and the hub of the unlocking-lever Q; but a modification is shown in Figs. 9, 10, and 11 in which a ratchet-wheel with external teeth is shown upon the hub of the hand-wheel and the unlocking-lever is shown with only a single tooth q' to engage the same and with a slotted eye q^2 , which permits the tooth to drop out of engagement with the ratchet-wheel, as shown in these figures, when the unlocking-lever is not in use.

In Fig. 11 a construction is shown which avoids applying a cap P' to the rear end of the spindle-support d, a collar p^2 being provided upon the locking-screw to fit the bottom of the socket in which the blank-spindle D is fitted, and the collar thus situated resists the outer thrust of the screw when the unlocking-lever Q is used to force the spindle D from its socket. In this construction the collar p' is formed directly upon the hub 35 of the hand-wheel P, which can be readily done where the cap P' is not employed.

In Figs. 1, 2, 3, and 4 the floor-pan is shown constructed as a base for the bed a, the base having a seat A, which forms a platform 40 raised above the floor, upon which the chips fall through an aperture g^3 in the carriage and an aperture a^3 in the top of the bed. Such platform is formed at a suitable distance above the floor to form the tank A' below such 45 platform to drain the oil or lubricator therefrom which may be mingled with the chips. The front end of the pan is formed with a trough A², projected beneath the gear-case l, which is used in such machines to contain the 50 feed-gearing for the carriage and from which oil is liable to drip. The pan, as shown in Figs. 2 and 4, is formed with the trough upon the right-hand side, (viewed from the gear-case l,) the left-hand side being that upon 55 which the operator usually stands and where any projection from the bed of the machine upon the floor impedes his access to the gear-blank and gear-cutter. The pan is therefore projected upon the left-hand side of the ma-

chine only sufficient to form a channel A³, which is connected with the rear end of the tank by a channel A⁴ at the rear end of the pan. The channels A³ and A⁴ form projections upon the pan sufficient to catch 60 any oil dripping from the machine above them. The sides of the floor-pan are undercut next the floor, thus narrowing the base

materially and causing the troughs around the edges of the pan to overhang the base, as shown in Figs. 1 and 3. The necessity of the overhang is especially great for the channel A³, as it permits of sufficient projection of the channel to catch the drip from the machine without preventing the operator from standing close to the bed a, as his toes can project beneath the channel or trough A³. The bottom of the trough A² as shown in Fig. 1 is sloped toward the bed a, and as shown in Fig. 3 toward the tank, which is shown extended nearly to the front end of the bed. The oil which runs from the platform A into the trough A² thus finds its way quickly to the tank and cannot stand in the trough. The bottom of the channel A³ is preferably sloped, as shown in Fig. 3, from the trough A² to the channel A⁴, so as not to discharge oil into the trough, which is more exposed to observation than the rear channel. Any of the oil which is supplied to the cutter and which flows from the edge of the carriage into the channel A³ is thus led to the rear end of the bed instead of to the front, where there is naturally very little drip into the floor-pan and where the appearance of oil would be most unsightly. Partitions or baffle-plates a^4 are shown in the tank near its ends where the oil flows into the same, and they are extended to a sufficient height to skim the oil and arrest the sediment, while the clear oil flows over the top of the partitions into the body of the tank.

The tank is shown in Figs. 1 and 3 with a cover a^5 supported upon the partitions by lugs s, with its ends slightly above the bottom of the trough to let the oil flow into the tank without running upon the top of the cover. The cover is formed with a slot s' to admit the suction-pipe t' of a pump t, which is attached to the cutter-carriage g and driven by gearing from the side shaft k. The discharge-pipe t^2 of the pump is shown carried up to the cutter in Fig. 1 to lubricate the same as it passes through the gear-blank. The cover is shown in Fig. 1^b divided into two parts at the center of the slot, which permits the cover to be applied to the tank without removing the suction-pipe t'. With such construction the separate halves of the cover can be removed to uncover the whole tank for removing sediment or oil and without displacing the suction-pipe t'. During the reciprocating movement of the carriage the suction-pipe moves back and forth in the slot between the partitions a^4 , where the oil is kept free from sediment by the partitions.

We are aware that it is old in many kinds of machines to provide an oil-pan beneath the same to catch the oil and to furnish such a pan with a tank in which the oil may be separated from the chips and that baffle-plates are also used to separate the oil from the chips, and we have therefore only claimed particular features of our construction.

The essential features of the floor-pan are the platform raised above the floor to receive the chips from the gear-cutter, the tank projected downwardly in the base below the level of such platform, the edge of the pan projected outwardly from the base to form a trough to receive the oil and conduct it to the tank, and the edge of the floor-pan undercut, particularly where the operator stands, to afford closer access to the bed. The undercutting of the base thus causes the trough of the pan to overhang that portion of the base which rests upon the floor and secures the projection of a pan around the bottom of the bed *a* without greatly extending the base which is formed by the floor-pan.

The attachments described greatly increase the capacity of the class of gear-cutters to which the invention applies and the convenience of operating the same.

Having thus set forth the nature of the invention, what is claimed herein is—

1. In a gear-cutter, the combination, with the horizontally-reciprocating cutter-carriage *g* having the main bearing *H*⁵ with the horizontal driving-arbor *h* supported therein and provided upon its inner end with a socket for the shank of a disk cutter, and having the seat *h*⁴ for a detachable outboard-bearing to support the end of an arbor disk-cutter spindle, the vertical bearing *H* having the foot *H*⁶ adapted to fit the seat of the outboard-bearing and the feet *h*⁴ fitted to the carriage at opposite sides of the main bearing, means for securing the feet detachably to the carriage in a uniform relation to the arbor *h*, the spindle *I* fitted to the vertical bearing and provided at the top with an end-milling cutter *H'*, and a pair of gears detachably connecting the spindle *I* and the driving-arbor interchangeably with the disk-cutter spindle, substantially as shown and described.

2. In a gear-cutter, the combination, with a cutter-carriage having a horizontal driving-arbor adapted to rotate a disk cutter, of a vertical bearing mounted removably upon the carriage, a vertical spindle therein carrying at the top an end-milling cutter, gearing connecting such spindle detachably with the driving-arbor, a housing inclosing such gearing to protect the same from the chips of the milling-cutter and provided with an oil-trough below the base of the cutter, and a guard upon the housing extended toward the base of the cutter, as and for the purpose set forth.

3. In a gear-cutter, the combination, with a horizontal bed *a* with a column *b* at one end having the head *c* adjustable vertically with the blank-spindle support *d*, and the bed having the carriage *g* fitted to reciprocate in ways *g*² parallel with the blank-spindle support and having the horizontal driving-arbor adapted to rotate a disk cutter, of a vertical bearing mounted removably upon the carriage, a vertical spindle therein carrying at the top an end-milling cutter, gearing con-

necting such spindle detachably with the driving-arbor, a housing inclosing such gearing to protect the same from the chips of the end-milling cutter, a driving-shaft with connections from the blank-spindle to the end-milling - cutter spindle to rotate the same, means actuated by the driving-shaft for feeding the carriage, and means actuated by the driving - shaft for turning the gear - blank spindle during the cutting operation to form gear-teeth spirally upon the blank.

4. In a gear-cutter, the combination, with a rotatable blank-support having an indexing or turning wheel thereon and a socket at one end for the blank-spindle, of a spindle-locking screw extended from the opposite end of the support with collar thereon, a cap attached to the support to form an outer bearing for the collar, means for turning the screw to lock the spindle in the socket, and an unlocking-lever fitted loosely upon the screw with means to engage it with the screw, when required, to force the gear-spindle from its socket.

5. In a gear-cutter, the combination, with a rotatable blank-support having an indexing or turning wheel thereon and a taper-socket at one end for the blank-spindle, of a spindle-locking screw extended from the opposite end of the support with collar thereon, a cap attached to the support to form an outer bearing for the collar, a hand-wheel secured upon the screw with ratchet-teeth upon the hub, and an unlocking-lever fitted loosely to the screw and adapted, when required, to engage such ratchet-teeth to force the gear-spindle from its socket, and to clear such ratchet-teeth in the normal rotations of the spindle-support.

6. A gear-cutter having a floor-pan with platform raised above the floor to receive the chips from the gear-cutter, a tank projected downwardly in the base below the level of the platform, and the edge of the pan being projected upwardly from the base to form a trough and overhung to permit the closer access of the operator to the bed.

7. A gear-cutter having a floor-pan with base having seat raised above the floor to support the gear-cutter bed and a platform to receive the chips from the cutter, a trough inclined downwardly from such platform and a tank in the base below the bottom of the trough, whereby the chips are drained upon the platform and the oil is accumulated wholly in the tank.

8. In a gear-cutter having a floor-pan with base having seat raised above the floor to support the gear-cutter bed and a platform to receive the chips from the cutter, a trough in the base around such bed and inclined downwardly from the level of the platform toward the rear end of the bed, a tank in the base below the bottom of the trough, and a cover for such tank with its edges raised to admit the oil from the trough.

9. In a gear-cutter, the combination, with a horizontal bed having a cutter-carriage mov-

able thereon, gearing upon the front end of the bed and a driving-shaft with connections thereto for reciprocating the carriage, of a floor-pan with base having seat raised above the floor to support the bed and a platform to receive the chips from the cutter, a trough extended from the front end of the bed beneath the carriage-feed gearing, a tank in the base at one side of the bed in connection with the trough, a channel extended from the trough around the opposite side and rear end of the bed to the rear end of the tank, and all parts of the trough being inclined from the platform downwardly toward the tank, as and for the purpose set forth.

10. In a gear-cutter, the combination, with a bed having a cutter-carriage movable thereon, and a driving-shaft and means connected thereto to feed the carriage, and a pump for feeding lubricant to the cutter upon the carriage, of a base supporting the bed at a suitable distance above the floor with a tank in the base below the level of the bed, and a trough projected upwardly from the bed 25 around the edges of the base, with an inclination from all parts of the trough toward the tank.

11. In a gear-cutter, the combination, with a bed having a cutter-carriage movable thereon, a driving-shaft and means connected thereto to feed the carriage, a pump for feeding lubricant to the cutter upon the carriage, and a base supporting the bed at a suitable distance above the floor with a tank in the base at one side of the bed below the level of the same, and a trough projected upwardly from the bed around the edges of the base with an inclination from all parts of the trough toward the tank, and the edge of the trough 35 being overhung to permit the closer access of the operator to the bed.

12. In a gear-cutter, the combination, with

a bed having a carriage movable thereon, of a driving-shaft and means connected thereto to feed the carriage, a pump for feeding lubricant to the cutter upon the carriage, a base supporting the bed at a suitable distance above the floor with a tank in the base below the level of the bed, and a trough projected upwardly from the bed around the edges of the base with an inclination from all parts of the trough toward the tank, vertical partitions in the tank near the ends to catch the sediment, and a suction-pipe from the pump upon the carriage arranged to move between the partitions as the carriage is reciprocated upon the bed.

13. In a gear-cutter, the combination, with a bed having a carriage movable thereon, of a driving-shaft and means connected thereto to feed the carriage, a pump for feeding lubricant to the cutter upon the carriage, a base supporting the bed at a suitable distance above the floor with a tank in the base below the level of the bed, and a trough projected upwardly from the bed around the edges of the base with an inclination from all parts of the trough toward the tank, vertical partitions in the tank near the ends to catch the sediment, a cover-plate over the tank with a slot extended between the partitions and division upon the line of the slot, and a suction-pipe from the pump upon the carriage arranged to move within the slot as the carriage is reciprocated upon the bed.

In testimony whereof we have hereunto set our hands in the presence of two subscribing witnesses.

HENRY E. EBERHARDT.
